UNITED STATES PATENT OFFICE.

MENZO SPRING, OF SAN FRANCISCO, CALIFORNIA.

ARTIFICIAL-LEG CORD.

SPECIFICATION forming part of Letters Patent No. 312,396, dated February 17, 1885.

Application filed August 29, 1884. (Model.)

To all whom it may concern:

Be it known that I, MENZO SPRING, of the city and county of San Francisco, and State of California, have invented an Improvement in 5 Artificial-Leg Cords; and I hereby declare the following to be a full, clear, and exact description thereof.

My invention relates to an improved cord which joins the foot to the leg portion of artificial legs; and my invention consists in a peculiarly plaited or braided outer covering or casing for the body or core of the cord, and in the connection between the top of the cord and the head of the screw, as I shall hereinafter 15 fully explain. Cords which are used for this purpose consist of a core of linen thread suitably wound, with or without an encircling casing of thread. Over this core or body is a 20 casing of leather glued to the core and formed of a strip having a single longitudinal seam. At the lower end of the cord is a loop, by which it is attached to the foot, and this loop is covered also by leather, which in the ordinary 25 construction must be of a piece separate from that forming the casing of the main portion of the cord, and there is therefor a lap-joint generally formed between the two. Besides 30 the difficulty of making two casings—one for the body of the cord and the other for the loop—there are other disadvantages of the ordinary cord. It is found in setting the tightening-nut upon its screw the cord is inclined to twist, and in time the casing, which is not 35 adapted to resist a twisting strain, becomes loose and finally breaks. Again, in the ordinary cord the upper end is doubled on itself, and incloses a wedge, which is pulled down by the cord into the hollow head of the screw, and is there suitably secured by cementing or 40 otherwise. This attachment is imperfect, requiring much time and great care in making, and even then it is liable to become loose and pull through the screw or burst the screw-head by reason of the great strain upon the 45 cord.

The object of my invention is to provide a casing for the body or core of the cord which by being plaited or braided is not only adapted to resist the twisting strain, but will even 50 tighten on itself, and cannot become rigid or stiff as the nut is turned in either direction,

forward or back; and the further object is to provide a simple and effective connection between the top of the cord and the screw.

Referring to the accompanying drawings for 55 a more complete explanation of my invention, Figure 1 is a perspective view of my cord. Fig. 2 is a view of the casing or covering B. Fig. 3 is a view of a foot and a portion of the leg, showing the application of cords A. Fig. 60 4 represents the upper portion of my improvement in section.

The cord A consists of the usual core of thread properly wound. It has a casing or covering, B, which consists of a single strip 65 of leather or other suitable flexible material, which is slit longitudinally in any number of strips, preferably in four, two from each end, toward the center, as in Fig. 2, leaving an uncut portion equal to the circumference of and 70 covering the loop C. The strip ends of this covering are braided or plaited around the body or core of the cord, two strips running one way and two the other, thus forming a complete covering or casing, Fig. 1. The upper end of the cord is inserted in the hollow screw D, and the threads of its core are passed 75 around the pin E, (preferably of metal,) which is seated in bearings f in the head F of the screw. The threads thus passing around and 80 the pin itself are glued or otherwise cemented to their places.

G is a nut upon the screw, by which the cord is tightened in the usual manner. As this nut is turned one way or the other to tighten 85 or loosen the cord, the twisting tendency upon the cord is borne by the casing B in such a manner as not to be injured thereby nor loosened, as it yields easily in two of its strips and tightens in the others, no matter whether the 90 nut is turned up or down, and this tightening of the casing obviates the necessity of using glue to secure it to the core, and it will therefore wear a longer time than the ordinary cords of this description. The making of the casing 95 B of one piece is also an advantage in economy and labor, while the manner of securing the cord to the nut is simple and effective.

The application of the cord to the leg is in the usual well-known manner shown in Fig. 100 3, in which the cords are secured to the foot P, and thence pass up through the plate Q in

the leg, and receive the usual rubber spring or cushion, R, between the plate and the tightening-nut.

Having thus described my invention, what I claim as new, and desire to secure by Letters Patent, is—

1. An artificial-leg cord, A, having a loop, C, at one end, and the casing B, of leather or other suitable flexible material, said casing 10 being made of a single strip slit longitudinally from each end toward the center, the uncut center being fitted around the loop C, and the slit ends braided or plaited around the re-

mainder of the cord, substantially as herein described.

2. An artificial-leg cord, A, and the cross-pin E, around which its end is passed, in combination with the screw D, having a head, F, with bearings f, in which the cross-pin fits, substantially as herein described.

In witness whereof I have hereunto set my hand.

Witnesses:
